UNITED STATES PATENT OFFICE.

VITTORIO PASTRENGO, OF SAN FRANCISCO, CALIFORNIA.

AERIAL APPARATUS.

1,396,874.

Specification of Letters Patent.

Patented Nov. 15, 1921.

Application filed May 21, 1921. Serial No. 471,425.

To all whom it may concern:

Be it known that I, VITTORIO PASTRENGO, a subject of the King of Italy, residing in the city and county of San Francisco and 5 State of California, have invented a new and useful Improvement in an Aerial Apparatus, of which the following is a specification.

My invention relates to improvements in 10 aerial apparatus, with respect particularly to improvements in means for alighting upon either land or water without damage to the machine.

The primary object of my invention is to 15 provide an improved aerial apparatus adapted for landing upon either land or water.

Another object of my invention is to provide improved means for retarding impact and absorbing shock without the use of 20 wheels when descent is made upon the land.

A further object is to provide improved 25 means for retarding the descent of aerial raft of the character described upon the surface of water when descent is made thereon.

A still further object of my invention is to 30 prevent dipping of the wings into the water, and the submergence of said wings by waves when alighting or floating upon the water.

I accomplish these and other objects by 35 means of the device disclosed in the drawings forming a part of the present specification wherein like characters of reference are used to designate similar parts throughout said specification and drawings, and in which:

Figure 1 is a side elevation of my improved aerial apparatus equipped with my novel alighting means.

40 Fig. 2 is a front elevation of Fig. 1, portions being broken away to disclose the construction of my improved landing skids.

Fig. 3 is a broken vertical longitudinal section upon a larger scale through one of 45 the hulls disclosing the operation of my landing skids.

Fig. 4 is an enlarged detail of my improved wing supporting means.

Fig. 5 is a transverse section through one 50 of the hulls showing the landing skid mounted therein; and

Fig. 6 is a broken vertical longitudinal section taken between the hulls showing the rear skid.

55 Referring to the drawings the numeral 1 is used to designate the wings of an aerial

craft provided with a plurality of air propellers 2 driven by suitable motors 3 mounted upon the framework 4 for the craft. A pair of buoyant hulls 6 provided with elevating planes 7 and rudders 8 are rigidly connected to the framework in such manner that when the hulls 6 float in water the craft will be supported above the water.

The hulls 6 are each provided with a landing skid 9 slidably mounted within a compartment 11 formed within the hull 6, by longitudinal partitions 12 and transverse partitions 13. A plurality of air cylinders 14 provided with air cocks 16 are mounted above the compartments 11 upon sections of shaft 17. Springs 18 are interposed upon the shaft sections 17 to resiliently retain the cylinders 14 in spaced position and the ends 19 of the shaft sections 17 are resiliently 75 mounted between springs 21 upon vertical shafts 22 to compensate for any distortion due to the impact of the skids 9 when alighting. Pivottally connected braces 20 permit a slight longitudinal movement of the cylinders 19 due to shock or vibration. A piston head 23 connected to a skid 9 by a connecting rod 24 is slidably mounted within each cylinder 14 to normally occupy the lowermost portion of the cylinder, air being admitted 85 above the piston head 23 through the cocks 16.

Springs 25 are mounted upon the connecting rods 24 between the skids 9 and a horizontal partition 25 to resist an upward movement of the skids 9 within the compartments 11.

A landing skid 27 is pivotally mounted upon a shaft 28 secured between the hulls 6 in any suitable manner, said skid 27 extending rearwardly to the end of the hulls 6. Air cylinders 29 similar to the cylinders 14 are secured between the hulls 6 above the rearward end of the skid 27 and is provided with a piston head and connecting rod 31 100 pivotally connected to the skid 27. The connecting rod 31 is loosely guided by a brace 32 secured between the ends of the hulls 6, and a spring 33 is mounted between the skid 27 and the brace 32 to resiliently resist an 105 upward movement of the skid. The connecting rod 31 is pivotally connected to the skid 27 to permit an arcuate movement of the skid 27 about the pivot shaft 28. The air cylinders 29 are allowed sufficient movement to 110 retain alignment with the connecting rod 31 during such arcuate movement.

When alighting upon the land, the skids 9 and 27 will be depressed against the air pressure within the cylinders 14 and 29 and against the pressure of the springs 26 and 33 in this manner retarding the descent of the apparatus and reducing the impact against the land, and absorbing the shock. The weight of the apparatus will be carried upon the wings 1 as in flying until the forward 10 momentum has been checked by tractive resistance against the skids 9 and 27. The upward movement of the skids 9 is limited by the partitions 25 so that even when moved inwardly to the extreme position the hulls 6 15 will be supported above the level of the land, the weight being distributed and balanced upon the three skids.

The skids 9 and 27 are each provided with a plane 36 secured transversely thereto and 20 inclined slightly toward the forward end thereof. The planes 36 are provided as a means of alighting upon the water, the area being sufficient to retard the descent of the apparatus and prevent a sudden impact of 25 the hulls 6 with the water such as might result in damage to the hulls or a submergence of the entire apparatus. The planes are arranged at an angle adapted to cause the hulls to skip lightly over the water until the 30 forward momentum has been reduced by the resistance of the water against the plane 36. The lower surface of the planes 36 are arranged in a plurality of offset sections 35 adapted to give an increased horizontal projection without increasing the vertical projection of the angle defined by the plane. In this manner the resistance to downward displacement through the water is increased 35 without increasing the resistance to a forward movement. The resistance of the water against a downward movement of the planes 3 causes the skids 9 and 27 to be moved upwardly against the air pressure within the cylinders 14 and 29 and against the pressure 45 of the springs 26 and 33, the impact being retarded and the shock of descending upon the water being thereby absorbed in the same manner as when descent is made upon the land.

50 When alighting upon or floating upon water the ends of the wings 1 are often caused to dip into the water because of the unevenness of the surface due to waves. In rough weather the wings may even be partially submerged by a wave. To prevent this I have provided a buoyant pontoon 37 pivotally connected at the forward end to a bracket 38 secured upon the lower side of each lower wing 1 at the outer end thereof. The other end 55 of each pontoon 37 is resiliently secured to the wing 1 by means of a rod 39 pivotally connected to the pontoon and slidably movable against the pressure of a spring 41 secured upon the wing 1 by means of a U-shaped bracket 42. In this manner any dip-

ping of the wing into the water is resiliently retarded by the pontoon 37.

Having thus described my invention what I claim as new and desire to secure by Letters Patent is:

1. The combination with an aerial apparatus having wings and a propelling means, of a pair of buoyant hulls secured to said apparatus and arranged to float the same upon the surface of a body of water; 75 a landing skid slidably mounted within each hull and extending outwardly from the bottom thereof; air cylinders mounted within said hulls; a plunger mounted within each cylinder and secured to said skids whereby 80 upward movement of said skids when alighting upon land is resiliently retarded by the air within said cylinder; a skid pivotally and resiliently secured between the hulls at the rearward end thereof to absorb impact 85 and to support said rearward end when descent is made upon the land; and means secured to said skids to retard descent and to operate said skids to absorb impact when descent is made upon the water. 90

2. The combination with an aerial apparatus having wings and a propelling means, of a pair of buoyant hulls secured to said apparatus and arranged to float the same upon the surface of a body of water; 95 a landing skid slidably mounted within each hull and extending outwardly therefrom; a landing skid pivotally mounted between said hulls and arranged to engage the land adjacent the rearward end of the hulls; resilient means connecting each skid to the hulls, said resilient means comprising a plurality of air cylinders; a piston slidably mounted within each cylinder, and a connecting rod secured between each piston and the skids whereby upward displacement of the skids by impact when descent is made upon the land is resiliently retarded and the shock absorbed by the compression of air within the cylinders, and springs upon 110 the connecting rods above the skids to further resist displacement and reduce shocks; and means secured to said landing skids to retard descent and to operate said skids to absorb impact when descent is made 115 upon the water.

3. The combination with an aerial apparatus having wings and a propelling means, of a pair of buoyant hulls secured to said apparatus and arranged to float the 120 same upon the surface of a body of water; a landing skid slidably and resiliently mounted within each hull and extending outwardly from the bottom thereof, and a landing skid pivotally connected between said hulls and 125 extending below said hulls at the rearward end thereof; resilient connections interposed between the skids and the hulls to reduce impact upon the land and to absorb the shock of landing; and planes secured to said 130

skids to engage the surface of water to operate said skids to retard descent and to absorb shock when descent is made upon water.

4. The combination with an aerial apparatus having wings and a propelling means of a pair of hulls secured to said apparatus and arranged to float the same upon the surface of a body of water; a landing skid slidably mounted within each hull and extending outwardly from the bottom thereof; a landing skid pivotally mounted between the hulls and extending below said hulls at the rearward end thereof; resilient connections interposed between the skids and the hulls to reduce impact upon the land and to absorb the shock of landing when descent is made upon the land; planes secured to said skids, said planes being upwardly inclined toward the forward end and having their lower surfaces formed in offset sections to retard descent and to operate the skids to absorb shock when descent is made upon water.
5. The combination with an aerial apparatus having wings and a propelling means of a pair of hulls secured to said

apparatus and arranged to float the same upon the surface of a body of water; a landing skid slidably mounted within each hull and extending outwardly from the bottom thereof; a landing skid pivotally mounted between the hulls and extending below said hulls at the rearward end thereof; resilient connections interposed between the skids and the hulls to reduce impact upon the land and to absorb the shock of landing when descent is made upon the land; planes secured to said skids, said planes being upwardly inclined toward the forward end and having their lower surfaces formed in offset sections to retard descent and to operate the skids to absorb shock when descent is made upon water; and buoyant means secured to the outer ends of the wings upon the lower side thereof to prevent said wings from dipping into the water and from being submerged by waves when alighting and floating upon water.

In witness whereof I hereunto set my signature.

VITTORIO PASTRENGO.
